AUTOMATIC DOORLATCH

James R. Henderson, Hayti, Mo.

Application November 29, 1933, Serial No. 700,169

4 Claims. (Cl. 70—29)

This invention relates to an automatic door latch and has for an object to provide a device for the automatic opening of a door by pressing a pedal at the foot, thereby leaving the hands free for other purposes and when closing the door it is only necessary to swing or merely kick the door closed and the latch provided by this invention will automatically fasten the door.

A further object of this invention is to provide a latch particularly suited for use on doors of barns, garages, implement sheds, dairies and numerous other buildings wherever lumber is used in their construction. Any farmer or dairymen will readily appreciate its time saving and efficient operation. Opening a door with both hands full of harness or pails of milk or other objects is a very difficult task where the present various types of crude fasteners are used.

This invention can further be used to advantage where doors do not fit with such precision as would be necessary for mortise door sets, such as used on dwelling houses. Furthermore, it is much steadier and will stand up under hard usage where mortise door sets would be far too fragile.

25 A further object of this invention is that this type of lock may be applied to a series of stall doors for livestock, one latch being provided for each door.

A further object of this invention is that all 30 the operating parts are connected to or mounted on the wall of the building, nothing being attached directly to the door per se, so that there is nothing to shake loose or break.

A further object of this invention is to provide 35 a door latch made of a minimum number of moving parts, all of which may be made of metal if so desired.

Still a further object of this invention is to provide 40 a door latch which includes a lock built there-in so that the door may be positively locked when so desired against opening.

Still a further object of this invention is to provide 45 a door latch which will enable a person to open the door from inside the building.

With the foregoing and other objects in view, as will hereinafter become apparent, this invention comprises the constructions, combinations, and arrangements of parts hereinafter set forth, claimed and illustrated in the accompanying 50 drawings:

Fig. 1 is a front elevation of the invention as applied to a barn door.

Fig. 2 is a sectional view taken on the line 2—2 55 of Fig. 1.

Fig. 3 is a view of the back of the door showing the push member for opening door.

Fig. 4 is a rear view of the latch showing groove for a spring.

Fig. 5 is a front elevation of the latch, the latch being broken away to clearly show how the spring is fastened to the barn wall.

Fig. 6 is a sectional view taken on the line 6—6 of Fig. 5.

Fig. 7 is a sectional view taken on the line 7—7 10 of Fig. 4.

There is shown at 10 a conventional representation of a building having a door 11 and a wall 12 to which the latch comprising this invention has been applied. It will be understood that 15 the building 10 may be a barn, garage, implement shed, dairy, or any other type of building usually constructed of heavy but rough lumber and which is generally used for the storage of live stock, dairy or farm implements or materials, etc. In 20 buildings of this general nature it is often necessary and essential to carry objects into the building such as harness, milk pails, farm implements, etc., thereby causing the user to deposit the objects on the ground so as to have his hands free for 25 opening the door. With this invention the door can be quickly and easily opened by means of the foot without the necessity of dropping anything from the hands.

The door 11 is held in closed position by means 30 of a rotary latch member 14, the latch member 14 being shaped as shown, having one circular edge 15 somewhat greater than a half circle and two flat edges 16 and 17. This latch member is 35 pivotally mounted on a sleeve 18 through which passes a bolt 19, the bolt 19 extending completely through the sleeve 18 and the wall 12, to which it is fastened by means of a bolt 20 and washer 21.

The sleeve 18 is fixed against rotation by having its end forked as at 22 so as to cooperate with a 40 key pin 23 placed in the wall 12. The sleeve 18 terminates in a flange 24, the flange 24 being notched as at 25 so as to cooperate with the bolt 26 of a lock 27, the outer face 28 of the lock 14 being countersunk so as to admit the placing of the lock 45 27 therein, the lock 27 being operated by a key 28.

As will be apparent, the key pin 23 prevents the sleeve 18 from rotating and when the lock 27 is operated by the lock key 28 it advances the lock bolt 26 into the notch 25. Then the latch member 50 14 is likewise held against rotation and inasmuch as the adjoining edges 15 and 16 overlap the door 11 when in this position, the door 11 is held locked against being opened, it being observed that the door 11 is mounted on hinges 29 in such a manner 55

that it can be opened only in an external direction.

The latch member 14 is normally held in this latching position by means of a spring 30 which is secured within a countersunk concentric groove 31 on the back face 32 of the latch member 14 by holding means such as a screw 33. The other end of the spring 30 is secured by similar holding means such as a screw 34, to the wall 12.

As will be apparent from an inspection of Figures 1, 4 and 5, the spring 30 tends to rotate the latch member 14 in a clockwise direction. The rotation of the latch member 14 is limited by means of a T-shaped tongue 35 pivotally secured by a screw 36 to the wall 12. The screw 36 is so spaced from the bolt 19 that the T head 35 abuts against the flat edge 17 in the position shown in Figure 5 when the adjoining edges 15 and 16 overlap the door 11.

When the latch member 14 is rotated in a counterclockwise direction by the structure yet to be described, the T-shaped head tongue 35 then abuts against the flat edge 17 in the position shown in the dot-dash outline 35' in Figure 1, when the flat edge 16 is parallel to and slightly spaced from the edge of the door 11, it being observed that the distance between the center of the bolt 19 and the nearest point of the flat edge 16 is less than the distance between the center of the bolt 19 and the edge of the door 11, thus permitting the latch member 14 to be rotated in a counterclockwise direction to entirely clear the door 11, permitting the door to be opened.

In order to rotate the latch member 14 in a counterclockwise direction against the action of the spring 30 a chain or other flexible member 37 is secured to a hook 38 in the circular edge 15 of the latch member 14, while the other end is secured to a foot pedal 39, which is pivotally mounted as at 40 on the side of the wall 12. As will be apparent, pressing the foot on the lever 39 will depress it to the position 39', causing the latch member 14 to rotate to the position 14' and retracting the edge 16 to the position 16' clear of the door 11, permitting the door to be opened.

In order to automatically open the door 11, an arm 41 is pivotally mounted in a U-shaped bracket 42 on the inside of the wall 12, a pin 43 passing through a pair of aligned openings 44 in the U-shaped bracket 42 and through an opening in the arm 41.

As will be observed, three pairs of holes 44 are provided in the U bracket 42, thus permitting proper adjustment of the arm 41, as may be desired.

One end 45 of the arm 41 presses against a coil spring 46 secured between the end 45 of arm 41 and the inside of the wall 12, the wall 12 being countersunk as at 47 to receive the end of the coil spring therein. This coil spring 46 tends to press the end 45 of the arm 41 away from the wall 12, thus pressing the other end 48 of the arm 41 against the door 11, the pressure of the spring 46 being such as to pivot the arm 41 against the door 11 whenever the latch member 14 is in the position 14'.

In order to eliminate friction between the end 48 of the arm 41 and the door 11, a roller 49 is provided on the end 48 for making actual contact against the door 11, the roller 49 being moved to the position 49' whenever the latch member 14 is moved to the position 14', thus giving the door 11 an initial impetus or kick to open the same.

A pin 50 fastened in the arm 41 adjacent the end 48 passes through a properly situated open-

ing in the wall 12. The back face 32 of the latch member 14 is provided with a countersunk metal strip 51 provided with a series of apertures 52.

When the door 11 has been opened by the arm 41 moving to the position 41', the end of the pin 50 moves into one of the openings 52, thus holding the latch member 14 in the position 14' while the door 11 remains in the opened position. When the door 11 is moved to the closed position it presses against the roller 49, pushing the arm 41 back from the position of 41' and removing the pin 50 from the apertures 52. This permits the spring 30 to then rotate the latch member 14 back from the position 14' to the locking position shown in Figure 5. Thus the latch member 14 will be automatically held in the position 14' as long as the door is opened and will automatically advance to the latched position whenever the door 11 is pressed to closed position against the action of the arm 41.

The flexible member 37 attached to the foot pedal 39 serves to actuate the latch member 14 whenever the pedal 39 is depressed by a person outside the building. If it is desired to actuate the latch from a position within the building 12, another flexible member 53 is provided which passes through a long curved slot 54 to the inside of the wall 12 and ends in a handle member 55, such as a large rubber ball or the like, preventing the flexible member 53 from accidentally being pulled through the slot 54. A person inside the building merely grasps the handle 55, pulls the flexible member 53 through the slot 54, rotating the latch member 14 to the position of 14' in the same manner that the flexible member 37 operates it.

As will be obvious from the drawings and disclosure, the end 48 of the arm 41 projects into the doorway occupied by the door 11 while the door 11 is in opened position, thus partly obstructing the opening through the doorway. It is sometimes necessary to have the entire door space clear of any obstruction when taking a large article therethrough and to relieve the doorway of any obstruction, the end 48 may be folded back to the position of 48' shown in Figure 2.

The end 48 of the arm 41 is secured thereto by means of a U-shaped bracket 56 pivotally secured to the arm 41 as at 57. The end 48 is held against movement about the pivot 57 by means of a heart-shaped spring 58 whose apex is secured at 59 to the arm 41. Two inturned ends 60 are secured by means of staples 61 to the arm 41, the arms 62 of the spring 58 being such that they normally project beyond the outsides of the arm 41 and thus overlap the U bracket 56, preventing the U bracket 56 from folding about its pivot 57 to the position shown in dash outline in Figure 2.

When it is desired to fold the end 48 to the position 48', however, it is only necessary to manually grasp the ends 60 of the arms 62, causing them to approach each other so that they no longer project beyond the outsides of the arm 41. The end 48 may then be folded about clear of the doorway. Afterwards, when it is desired to restore the arm 41 to normal operative position, it is only necessary to press the end 48 back to the straight position and the spring arms 62 will automatically lock it in this straight position.

The novel features and the operation of this device will be apparent from the foregoing description. While the device has been shown and

the structure described in detail, it is obvious that this is not to be considered limited to the exact form disclosed and that any changes may be made therein within the scope of what is claimed 5 without departing from the spirit of this invention.

Having thus set forth and disclosed the nature of this invention, what is claimed is:

JAMES R. HENDERSON.
